US00D882225S

(12) **United States Design Patent** (10) **Patent No.:** **US D882,225 S**
Small (45) **Date of Patent:** **** Apr. 28, 2020**

(54) **SHOE** 4,439,936 A * 4/1984 Clarke A43B 5/06
 36/102
 (71) Applicant: **NIKE, Inc.**, Beaverton, OR (US) 4,494,320 A 1/1985 Davis
 D286,342 S 10/1986 Stubblefield
 (72) Inventor: **Jessica Small**, Portland, OR (US) D287,304 S 12/1986 Peterson et al.
 D291,146 S * 8/1987 Selbiger ..... 36/32 R
 D291,147 S 8/1987 Kelley et al.
 D291,941 S 9/1987 Peterson

(73) Assignee: **NIKE, Inc.**, Beaverton, OR (US)

(Continued)

(**) Term: **15 Years**

(21) Appl. No.: **29/680,286**

FOREIGN PATENT DOCUMENTS

(22) Filed: **Feb. 14, 2019**

CN 203646610 6/2014
 CN 204653921 9/2015

(74) *Attorney, Agent, or Firm* — Banner & Witcoff, Ltd.

(57) CLAIM

The ornamental design for a shoe, as shown and described.

DESCRIPTION

FIG. 1 is a first side view of a shoe showing my design; FIG. 2 is a second side view thereof; FIG. 3 is a rear view thereof; and, FIG. 4 is a bottom view thereof.

The even-length broken lines of the shoe depict environment, represent unclaimed subject matter, and form no part of the claimed design.

1 Claim, 4 Drawing Sheets
